attorney.

UNITED STATES PATENT OFFICE.

GEORGE F. RICHARDSON, OF MARTINSVILLE, INDIANA, ASSIGNOR TO
EDWIN L. BROWN, OF SAME PLACE.

DESIGN FOR A CHAIR.

SPECIFICATION forming part of Design No. 24,554, dated August 13, 1895.

Application filed May 13, 1895. Serial No. 549,190. Term of patent 3½ years.

To all whom it may concern:

Be it known that I, GEORGE F. RICHARDSON, a citizen of the United States, residing at Martinsville, in the county of Morgan and State of Indiana, have invented and produced a new and useful Design for Chairs; and I do hereby declare the following to be a full, clear, and exact description of the invention, such as will enable others skilled in the art to which it ⁵ap-
¹⁰pertains to make and use the same.

The leading feature of my design consists of the four vertical posts forming the legs of the chair, all of which are covered with the natural bark of the hickory sapling, the two ¹⁵back legs **A A** terminating at their upper ends with the turned acorn-shaped ornaments **a a**, whereby the white under wood of the legs or posts will be brought out in sharp contrast with the darker outer bark. The posts **B B** ²⁰will also terminate with the conoidal-turned portions **b b**, showing the light under wood in bright contrast with the bark.

The rounds **C**, arms **D**, and cross-bars **E** are all covered with the rough natural bark of the hickory, with the exception of the ends of the ²⁵arms **D**, which expose the white under wood in the manner as described for the posts of the chair.

The bottom and back will be woven from hickory splints in the pattern clearly shown ³⁰in the drawing.

The same design can be used for chairs with or without rockers.

What I claim is—

The design for a chair, substantially as ³⁵shown and described.

In testimony whereof I affix my signature in presence of two witnesses.

GEO. F. RICHARDSON.

Witnesses:

E. S. BROWN,
JOSEPH A. MINTURN.
